UNITED STATES PATENT OFFICE

JACOB STARR, OF BRONX, NEW YORK, ASSIGNOR OF ONE-HALF TO JULIUS MARGOLIN,
OF NEW YORK, N. Y.

ATTACHMENT FOR RAISING AND LOWERING AWNINGS AND THE LIKE

Application filed April 20, 1932. Serial No. 606,466.

This invention relates to new and useful improvements in an attachment for raising and lowering awnings and the like.

This invention relates to similar subject 5 matter in my Patent No. 1,849,255 dated March 15th, 1932.

The invention has for an object the construction of a device of the class mentioned which is constructed of simple durable construction, dependable in use and efficient in 10 operation and which can be manufactured and sold at a reasonable cost.

For further comprehension of the invention, and of the objects and advantages there- 15 of, reference will be had to the following description and accompanying drawing, and to the appended claims in which the various novel features of the invention are more particularly set forth.

20 In the accompanying drawing forming a material part of this disclosure:—

Fig. 1 is a side elevational view of a device constructed according to this invention, the wiring thereof being shown schematically.

25 Fig. 2 is an elevational view looking in the direction of the line 2—2 of Fig. 1.

Fig. 3 is a view similar to a portion of Fig. 1 but drawn on an enlarged scale.

Fig. 4 is a sectional view taken on the line 30 4—4 of Fig. 3.

Fig. 5 is a schematic wiring diagram of the device.

Fig. 6 is a view similar to a portion of Fig. 1 but illustrating a modified arrangement.

35 Fig. 7 is a side elevational view of the reversing switch, per se, shown in Fig. 3.

The invention is applied to an awning such as is customarily placed outside of store windows and the like and which includes a 40 frame 10 pivotally mounted at its lower ends

11 and at the top connected with awning material not shown on the drawing, which material is wound on a roller 12 supported at the top of the window. The awning can be 45 raised and lowered by turning of the roller 12 to cause the awning material to wind thereon or thereoff.

A means is provided for raising and lowering the awning by causing rotation of the 50 roller 12 and comprises particularly a

sprocket wheel 13 fixed upon the shaft of the roller 12 and engaged by a chain 14 extending to the interior of the building equipped with the awning and engaging over another sprocket wheel 15 fixed upon the shaft 16 of a 55 speed reduction unit 17 in connection with an electric motor 18. Thus rotations from the motor are transmitted to cause turning of the roller 12. In Fig. 6, a variation of this transmission means has been disclosed in 60 which a bevel gear 19 is shown fixed upon the shaft of the roller 12 and in mesh with another bevel gear 20 upon a shaft 21 extending into the building and carrying a bevel gear 22 meshing with a bevel gear 23 upon 65 the shaft 16 of the speed reduction 17. In other respects, the form shown in Fig. 6 is identical to the previously described form.

The electric motor 18 is in a circuit which includes an electric plug 24 for connection 70 with some source of power and a switch 25 operable to cause operation of the automatic means for raising and lowering the awning. More particularly, the circuit includes a reversing switch 26 arranged so that when 75 drawn in one direction, causes rotation of the motor one way and when thrown in the other direction, rotation in the opposite manner. A means is provided for operating the switch 26 to control the raising and lowering 80 of the awning. Specifically, this means comprises a speed reduction unit connected with the shaft 16 and comprising a sprocket 27 fixed upon the shaft and engaging with a chain 28 engaged over a large sprocket 29. 85 Fixed upon the shaft of the large sprocket 29 there is a small sprocket 30 engaging with an endless member 31. A bracket 32 serves to rotatively support the sprockets 29 and 30. The provision of the chain 28 and the 90 sprockets 29 and 30 are for the purpose of reducing the rate of motion of the endless member 31. At the other end the endless member 31 is engaged on a sprocket 32 supported by a bracket 33.

95 A pair of fingers 34, 35 are mounted upon one side of the endless member 31 and are arranged on opposite sides of the reversing switch 26 so as to be selectively engageable with the switch for setting the switch in one 100

or in its other position. Each of the fingers 34, 35 is pivotally supported at its inner end upon a peg 36 projecting from a bracket 37 engaged on the endless member and held in various adjusted positions as desired by a set screw 38. A spring 39 is mounted on each of the pegs 36 and serves to resiliently urge the fingers frictionally against the brackets for maintaining the fingers in various adjusted angular positions. The operative distance between the fingers may be adjusted by the angular adjustment without adjusting the brackets 37 on the endless member. A collar 40 is adjustably fixed on each of the fingers by a set screw 41 and connects with a stem 42 slidably mounted in a guide track 43 connected between the brackets 32 and 33 so as to insure positive and firm motion of the fingers 34 and 35 as the endless member moves.

20 The reversing switch 26 includes a pair of poles 44 pivotally mounted intermediately at 44', of their ends and engageable with contacts 44^a on one side by pivoting them to that side or with other contacts 44^b on the other side by pivoting them to the other side. A means is provided for snapping the poles 44 in one or the other position and comprises a fork 45 straddling a stem 46' mounted upon the poles 44. The fork 45 is pivotally mounted at its rear end 46 and is limited in motion by pegs 47 mounted on the base 48 of the switch which is secured upon the rear of the track 43. An operating lever 49 is mounted intermediately at 50 and its outer end 51 is engageable by the fingers 34, 35 while the inner end carries a spring 52 connected with the fork 45 in a manner so as to hold the fork towards one side and when the lever 51 is moved to the position shown by the 40 dot and dash lines 53, to hold the fork on the other side and thus control the operation of the switch.

45 The operation of the device consists in closing the switch 25 to cause operation of the mechanism for raising and lowering the awning. When the switch 25 is closed the circuit is closed through the motor 18 and the motor will rotate in one direction or the other depending on the position in which the switch 26 is in. Assume that the awning is in a completely raised position. In this condition the switch 26 will be closed so as to cause the awning to move downwards. As the awning moves downwards the motion will be transmitted to the endless member 31 and the finger 34 will approach the control lever 51 of the reversing switch. In any position the switch 25 will be opened to cause the awning to assume the particular position. If it is held until it is completely lowered the finger 34 will strike the control lever 51 and cause it to pivot to the position indicated by the dot and dash lines 53 in which the switch 26 is thrown to the other side whereupon the connection through the motor is changed. Then,

as the switch 25 is again closed the motor will rotate in the opposite direction and raise the awning. When completely raised the lower finger 35 will again throw the switch into its first position.

70 While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

75 Having thus described my invention, what I claim as new, and desire to secure by United States Letters Patent is:

1. In an awning adapted to be raised and lowered and having a roller for receiving the awning cover, means for raising and lowering the awning including an electric circuit controlled with a manually operable switch, a motor connected in said circuit and with said roller, a reversing switch having two positions and located in said circuit and connected with said motor to control the direction of rotation according to its position, and means for operating said switch comprising a speed reduction unit connected with said motor, an endless member connected with said speed reduction unit, a pair of fingers on said endless member and on opposite sides of said reversing switch and selectively consecutively engageable with said reversing switch to move it from one to the other position, and means for firmly guiding the fingers for actuating the switch.

80 2. In an awning adapted to be raised and lowered and having a roller for receiving the awning cover, means for raising and lowering the awning including an electric circuit controlled with a manually operable switch, a motor connected in said circuit and with said roller, a reversing switch having two positions and located in said circuit and connected with said motor to control the direction of rotation according to its position, and means for operating said switch comprising a speed reduction unit connected with said motor, an endless member connected with said speed reduction unit, a pair of fingers on said endless member and on opposite sides of said reversing switch and selectively consecutively engageable with said reversing switch to move it from one to the other position, and means for firmly guiding the fingers for actuating the switch, said speed reduction unit terminating in a sprocket, said endless member being engaged over said sprocket and over another sprocket spaced from said sprocket.

85 3. In an awning adapted to be raised and lowered and having a roller for receiving the awning cover, means for raising and lowering the awning including an electric circuit

controlled with a manually operable switch, a motor connected in said circuit and with said roller, a reversing switch having two positions and located in said circuit and connected with said motor to control the direction of rotation according to its position, and means for operating said switch comprising a speed reduction unit connected with said motor, an endless member connected with said speed reduction unit, a pair of fingers on said endless member and on opposite sides of said reversing switch and selectively consecutively engageable with said reversing switch to move it from one to the other position, and means for firmly guiding the fingers for actuating the switch, said speed reduction unit terminating in a sprocket, a bracket supporting said sprocket, said endless member being engaged over said sprocket and over another sprocket spaced therefrom, a bracket supporting said latter-mentioned sprocket, and said means for firmly guiding the fingers for actuating the switch being secured on said brackets.

4. In an awning adapted to be raised and lowered and having a roller for receiving the awning cover, means for raising and lowering the awning including an electric circuit controlled with a manually operable switch, a motor connected in said circuit and with said roller, a reversing switch having two positions and located in said circuit and connected with said motor to control the direction of rotation according to its position, and means for operating said switch comprising a speed reduction unit connected with said motor, an endless member connected with said speed reduction unit, a pair of fingers on said endless member and on opposite sides of said reversing switch and selectively consecutively engageable with said reversing switch to move it from one to the other position, and means for firmly guiding the fingers for actuating the switch, each of said fingers being adjustable relative to each other.

In testimony whereof I affix my signature.
JACOB STARR.
